UNITED STATES PATENT OFFICE

2,558,590

SELF-PROPELLED MANUALLY STEERED
PORTABLE RUG-WASHING MACHINE

Philip P. Smith, Atlanta, Ga.

Application August 20, 1946, Serial No. 691,766

1. Claim. (Cl. 15—320)

This invention relates to a self-propelled steam rug washer, the object thereof being to provide a machine especially designed to wash rugs on a concrete platform or floor. The machine is designed to be propelled over the rug in all directions in a forward motion while being supplied at its washing and propelling brush, with liquid soap and steam, so that when moved in a forward direction, the brush whips up the soap which is evenly distributed on the rug; throughout the operation, the supply of soap being controlled together with the supply of steam from a suitable source, after which a supply of steam without the soap is supplied while the machine is moved in the reverse or backward direction from the end of the rug. This operation is repeated until the rug is completely cleaned, after which only cold freshwater is supplied to the machine while running the machine backward or in one direction, so as to lay the nap in one direction and act as a squeegee, taking all water off of the rug and eliminating all wheel tracks.

Another object of the invention is to provide an electrically driven machine having a drive roller in the form of a brush, through which the necessary cleaning and sterilizing liquid cooperates while brushing the rug, so as to completely sterilize both sides of the rug or carpet, to kill all moths, larva and carpet beetles, to lay the nap in one direction, to provide an efficient way of cleaning without damage to the nap or fabric of the most expensive Oriental or Chinese rugs, while the rug is flat upon the floor or a concrete platform, by quickly and efficiently applying soap, water and steam to immediately remove all imbedded dirt and filth from the warp without injury or damage to the carpet or rug, as well as to the back of the rug, without injury or damage to the piling and enliven the coloring and appearance of the rug by the application of steam.

Another object of the invention is to provide a machine which is properly balanced and mounted to be moved on two wheels only instead of on four wheels and easily controlled to balance the motion thereof and pressure of the cleaning brush against the surface of the rug or carpet, in which the device is propelled by the brush making it necessary for the operator merely to steer the machine but at the same time to remove all dirt imbedded in the rug, while rendering the supply of soap, steam and water convenient at all times.

Other objects and advantages reside in the details of construction and operation as more fully hereinafter described and claimed, reference be-

ing had to accompanying drawings forming part hereof, wherein like numerals refer to like parts throughout, and in which:

Figure 1 is a top plan view of a self-propelled steam rug washer or washing machine constructed in accordance with the invention, partly broken away;

Figure 2 is a side elevation of the machine;

Figure 3 is a longitudinal vertical sectional view taken on the line 3—3 of Figure 1, and

Figure 4 is a fragmentary sectional view taken on the line 4—4 of Figure 1.

Referring to the drawings in detail, in which like reference characters designate corresponding parts throughout the several views, the machine is shown as comprising a bottom frame 10 having a front horizontal portion and an inclined rear portion 11 sloping forwardly, so that the rear portion 11 is disposed at a higher elevation and supports a housing 12 thereover, closed on all sides and provided with a hood 13 at the front and a top wall 14. The housing is reinforced by a transverse vertical wall 15 and in rear thereof with a transverse channel bar 16 which is inverted in position and between which and the partition 15 longitudinally arranged spaced parallel channel bars or sections 17 are provided giving strength to a U-shaped handle member 18 having its legs provided with vertical portions 19 anchored to the top wall 14 at the bar 16, by means of standard sockets or plates 20. The handle extends upwardly and rearwardly and then horizontally at the back, as indicated at 21, and is provided with a hand-gripping portion 22 disposed horizontally. However, it is to be understood that the handle may be otherwise suitably constructed and is provided with a transverse tubular cross-bar 23 as shown at the angular portion between the horizontal sides 21 and the inclined forward portions. The machine is supported upon pneumatic wheels and tires 24 by means of an axle 25 supported in bearings 26 at the ends of the axle and within the sides of the housing so that the chassis of the machine and housing is supported to be readily moved about.

The partition 15 forms a chamber 27 with the front and top of the housing forwardly of the longitudinal center and the chassis and housing are pivoted upon the axle 25 rearwardly of the longitudinal center so that the front is normally held downwardly and partly counterbalanced by the weight of a motor 28, preferably an electric motor supported centrally upon the top 14 of the housing 12 at the back with a box 29 housing the binding posts or connections of the

electric leads to the motor, housed therein and extending through a conduit 39 which extends forwardly extending toward the front of the housing and machine or chassis thereof, to a pullbox or socket 31, to which a cable may be connected or plugged in, with a suitable extension cable leading from the wall socket of the supply circuit. The extension cord is preferably arranged overhead or vertically, so as not to permit the wiring to become fouled in the shafts and belts of the machine and the weight of the motor tends to partially counter-balance the overbalancing weight of the machine which maintains the front thereof downwardly toward the floor, and thus the rug or carpet to be cleaned. The motor shaft bears a pulley 32 on which an endless drive member or V-belt 33 is engaged together with a pulley 34 fixed on a transverse counter-shaft 35 rotatably supported in bearings 36 upon the top wall 14 of the housing 12 and projecting outwardly thereof at the sides of the housing to mount pulleys 37. Belts 38 are engaged on the pulleys 37 and around pulleys 39 mounted on the ends of a transverse shaft 40 horizontally journaled across the lower portion of the chamber 27 at the sides of the housing 12 when journaled in bearings 41 at the outside of the housing, and from which the ends of the shaft 40 project to take the pulleys 39. The shaft 40 supports the rotary cylindrical brush 42 which is made up of the steel shaft on which are mounted a plurality, preferably five equi-distantly spaced collars 43 secured by set screws or the like 44 to the shaft and drilled and tapped peripherally for attachment by screws or otherwise, of a plurality of peripherally spaced longitudinally wooden brush lags or staves 45, preferably five in number, providing longitudinal slots 46 therebetween, and between the brush sections or tufts 47 carried thereby. Thus the cylindrical brush, is made of a series of sections or brushes running longitudinally, and this arrangement facilitates the quick and easy removal and replacement of the legs or brush sections due to wear, deterioration or otherwise.

Mounted on the top of the chassis or housing 12 at the top wall 14 in front of the counter-shaft 35 centrally and transversely thereof, is a manifold 48 from which extend vertical branches or pipes 49, 50 and 51 connected by flexible hose with supply means for forcing under-pressure, steam, water and soap solution to the manifold. A pipe 52 leads centrally from the bottom of the manifold 48 and is supported at 53 on the top wall 14 of the housing 12, through which it leads to extend under the hood 13 within the chamber 27 as indicated at 54 to connect to a horizontal pipe 55 mounted in back of the lower portion of the front wall of the hood 13 adjacent the frame 10 and provided with a plurality of spaced perforations 56 at the bottom so as to constitute a nozzle tube to accurately direct the spray of properly mixed steam, soap solution and water or either individually, to the surface of the rug or carpet being washed and cleaned. This nozzle is positioned in front of the brush 42, and the partition 15 forms a baffle wall within the housing behind the brush to minimize splashing from the brush and partially hold the hot vapors given off by the steam mixture within the chamber 27. The supply of steam, water and soap may be controlled individually and independently by interposing valves 57 in the pipe connections 49, 50 and 51 to the manifold 48 so that the amounts of steam, water and soap may be normally ad-

justed by the valves above the manifold and connecting to the operating handles or arms 58 of the valves 57, are rearwardly extending control rods or levers 59 which extend rearwardly through aligned openings in the tubular cross-bar 23 or other suitable guides provided thereon and extending rearwardly thereof, where they are provided with handles 60 in front of the hand-gripping portion 22 of the handle-bar, to be easily reached by the operator from the handle. It is also to be understood that the pipe connections 49, 50 and 51 are connected to suitable hoses, preferably overhead, the flexibility of which permits movement of the machine relative to the supply connections, including the water main and supplies for steam and soap.

In the use of the washer, the brush 42 by reason of the counter-balancing of the weight of the machine through the medium of the motor 20 and handle, will be caused to engage the rug or carpet at the proper pressure to exert such pressure against the carpet in the exact amount required for efficient operation. The water, soap and steam is applied to the surface of the carpet 25 or rug by operating the valves 57 from the handles 60 to be discharged through the perforations of the nozzle or pipe 55 as the machine is advanced across the rug or carpet. The machine is propelled by the motor which drives the brush due 30 to the contact of said brush with the rug surface so that it is only necessary for the operator to steer the machine which is designed to wash the rugs on a concrete platform or while laid out flat. As the machine is propelled forward, the rotating 35 brush whips up the soap which is distributed evenly on the rug with the supply and control as stated. The steam is simultaneously applied to the rug continuously while the machine is in motion and at the end of the rug, the forward motion 40 of the machine is reversed. On the reverse action, the soap is cutoff, while the steam is still being supplied and this operation is repeated until the rug is completely cleaned. The last operation is similar to the first, using only cold fresh 45 water and running the machine in one direction so as to lay the nap in one direction. Also, since the brush sections of the rotating cylindrical brush may be replaced without dismantling the machine, the renewal or replacement of the 50 brushes is greatly facilitated simply by removing the lags or staves 45.

While in the foregoing there has been shown and described the preferred embodiment of this invention it is to be understood that minor 55 changes in the details of construction, combination and arrangement of parts may be resorted to without departing from the spirit and scope of the invention as claimed.

What I claim as my invention is:

60 In a machine for washing a rug laid on a floor, a housing open at the bottom and having a transverse vertical partition therein defining front and rear compartments, a rotary transverse cylindrical brush in said front compartment, co-axial 65 supporting wheels for the housing located within and at the sides of the rear compartment and journaled upon a transverse axis located rearwardly of the longitudinal center of the housing so that the latter is overbalanced at the front 70 to cause engagement of the brush with the rug, a motor mounted on top of the housing rearwardly of the axis of said supporting wheels and partly counterbalancing the front of said housing, a driving connection between said motor and 75 said brush whereby the latter is driven in a di-

rection to propel the machine forwardly, a guiding handle attached to the top of and extending upwardly and rearwardly from the housing, a discharge nozzle located transversely of and within in the front compartment in front of said brush, and valve-controlled means for selectively or simultaneously supplying steam, soap and/or water to said nozzle from fixed sources extraneous to the machine, said valve-controlled means including a manifold mounted above and near the front of the housing and having an outlet connected to the nozzle, steam and soap and water supply pipes connected to said manifold and having individual control valves, separate operating rods for said valves extending rearwardly within reach of an operator grasping the handle, and guide means for said operating rods carried by the handle.

PHILIP P. SMITH.
